C. E. GODLEY.
LAMP WITH SWINGING REFLECTOR.
APPLICATION FILED APR. 13, 1917.

Patented Nov. 6, 1917.

UNITED STATES PATENT OFFICE.

CHARLES E. GODLEY, OF DETROIT, MICHIGAN, ASSIGNOR TO EDMUNDS AND JONES CORPORATION, OF DETROIT, MICHIGAN, A CORPORATION OF NEW YORK.

LAMP WITH SWINGING REFLECTOR.

1,245,331.

Specification of Letters Patent. Patented Nov. 6, 1917.

Application filed April 13, 1917. Serial No. 161,738.

To all whom it may concern:

Be it known that I, CHARLES E. GODLEY, a citizen of the United States, and residing at Detroit, in the county of Wayne and State 5 of Michigan, have invented a new and Improved Lamp with Swinging Reflector, of which the following is a specification.

This invention relates to means for varying the direction and the intensity of beams 10 of light projected by electric lamps of the headlight type and its object is to provide a lamp which will project an intense concentrated beam or diffused mild light as desired, and which will have a minimum of 15 movable parts.

This invention consists, in combination with a lamp body, of a reflector hinged at its outer edge in said body, a lamp bulb support 20 slidable in the rear end of the reflector and pivotally mounted at its outer end in the lamp body, and means to swing the reflector and the bulb support. It also consists in a supporting hinge connected to the reflector at the top of its rim so that the bulb 25 will move forward and upward relative to the reflector when the reflector is swung back, thereby causing the major portion of the light to be projected downward. It further consists in the details of construction 30 illustrated in the accompanying drawing and particularly pointed out in the claims.

In the drawing, Figure 1 is a vertical axial section of this improved lamp. Fig. 2 is a rear elevation of the hinge. Fig. 3. 35 is a rear elevation of the arm to which the resilient connector is attached. Fig. 4 is an axial section of the hinge on a larger scale. Fig. 5 is a section on the line 5—5 of Fig. 1.

Similar reference characters refer to like 40 parts throughout the several views.

It has been suggested that reflectors be mounted on pivots which are in an axial plane of the lamp body and that cams be provided to move the lamp bulb toward and 45 from the focus of the reflector as the reflector is swung on its pivots. In the present construction the reflector is pivotally mounted or hinged at or near its rim so that the reflector may be swung backward and forward.

The lamp body 1 may be of any desired construction but is preferably cup shaped, and its rim terminates in an inwardly extending flange 2. A rim 3 provided with a 50 flange 4 is securely mounted in the body in

any desired manner, and a door consisting of the lens 5 and ring 6 fits over the open front end of the body.

Carried by the body and preferably mounted on the outside of the ring 3 are 60 two lugs 7 which support the pivot or hinge 8. The cup shaped reflector 9, which is preferably parabolic, has a back-turned cylindrical flange 10 of slightly smaller external diameter than the internal diameter 65 of the ring 3 and secured to the inside of this flange 10 is a plate 11 having a down-turned part 12 that terminates in the sleeve 13 that receives the pin 8 and thus supports the reflector. 70

At the bottom of the reflector and diametrically opposite the middle of the pin 8, a rearwardly extending arm 14 is secured to the ring 3, while just within it a longer arm 15 is secured to the flange 10 and also 75 extends rearwardly. A spring 16 connects the outer end of the arm 14 and the finger 17 on the arm 15 and tends to pull the lower part of the edge of the reflector forward until its axis coincides with that of the body. 80 A flexible connector 18 in the form of a cord or wire extends from the free end of the arm 15 back through a hole 20 in the body 1 and by means of this connector the reflector 85 may be swung back to the position indicated in dotted lines in Fig. 1.

The rear end of the reflector is formed with an opening through which extends the connector 22 of well known construction. The metal of the reflector around this hole 90 is bent back to constitute a flange 23 that secures a reinforcing ring 24 in position. The flange 23 and ring 24 are notched to receive the key 25 secured to the outside of the connector 22 to prevent it from turning. 95 A bulb 27 is mounted in the front end of the connector 22 and a plug 28 in the rear end. A wire 29 extends from the coupling 30 mounted in the body 1. A bar 32 is secured to the connector 22 and its inturned end 33 100 is threaded to receive the focusing screw 34 having a head 35 on the outside of the body 1. A spring 36 on this screw acts as a brake and normally keeps the screw from turning. A pin 37 limits the movement of 105 the part 33 on the screw. A spring 38 extends from the key 25 to the ear 39 and serves to prevent the connector from rattling.

After the lamp has been mounted, for in- 110

stance at the front end of an automobile, the cord or wire 18 is released so that the spring 16 may swing the parts to the position shown in Fig. 1. The lamp bulb 27 is then focused by means of the screw 34 so that a concentrated beam of light will be projected onto a spot in the roadway the desired distance ahead of the vehicle.

When the cord 18 is pulled back to swing the reflector to the position indicated in dotted lines in Fig. 1, the ring 24 is swung up and causes the lamp bulb to swing on the screw head 35. The relative movement of the bulb is both forward and upward from the focal center of the reflector. This results in a very diffused light being projected by the reflector and in most of this light being thrown downwardly onto the roadway just in front of the vehicle. The normal position of the reflector and lamp bulb shown in solid lines in Fig. 1 is best adapted for "country" driving while the dotted-line position is best adapted for "city" driving where concentrated beams are objectionable.

The ring 24 and the lip 23 are so formed that the connector may swing within the smallest possible hole in the rear end of the reflector. The distance that the bulb moves away from the axis of the reflector will be increased as the distance between the rear ends of the reflector and lamp body is decreased. The proportion of light thrown down onto the roadway may be increased therefore by shortening this distance between reflector and body. The lamp may be mounted with the plane of the path of the axis of the reflector at any desired angle to the horizontal, but in the claims this plane will be considered as vertical.

I claim:

1. In a lamp, the combination of a body and a reflector therein, a hinge connecting the rim of the reflector to the rim of the body, a connector slidably mounted in an opening in the rear end of the reflector and pivotally mounted in the body of the lamp, a lamp bulb carried in the front end of the connector, and means to swing the reflector on its hinge and the connector on its pivot.

2. In a lamp, the combination of a body and a reflector therein, means connecting their rims at one point, means to swing the reflector backwardly and forwardly in said body, a lamp-bulb within the reflector, and means supported at one end by the lamp body and extending through an opening in the reflector to receive said bulb, said means

being adapted to swing relative to the reflector.

3. In a lamp, the combination of a body and a parabolic reflector therein, a hinge connecting the rims of the body and reflector at one point, a lamp bulb within the reflector, and means to swing the reflector on its hinge relative to the lamp body and to move the lamp bulb transversely to the focal axis of the reflector.

4. In a lamp, the combination of a body and a reflector therein, a flexible connection between the rims of the body and reflector, means to swing the reflector relative to the body, a lamp bulb and a support therefor pivotally mounted in said reflector and means connecting the support to the body of the lamp.

5. In a lamp, the combination of a body and a reflector therein, a flexible connection between the rims of the body and reflector, means to swing the reflector relative to the body, a lamp bulb and a support therefor pivotally mounted in said reflector and an adjustable connection between said support and the body of the lamp whereby the bulb may be focused.

6. In a lamp, the combination of a cup-shaped body, a ring mounted in the open end thereof, a door for closing said open end, a pin carried by said ring, a parabolic reflector mounted on and below said pin, means for swinging the reflector on said pin back and forth in said body, a spring connected to said ring and reflector for swinging the reflector forwardly in said body, a connector slidably in an opening in the rear end of the reflector, means to prevent the connector from turning in said opening, a spring to press the reflector against the wall of said opening, a bulb in the front end of the connector, and means to cause the bulb to move upwardly and forwardly relative to the reflector when the reflector is swung backwardly.

7. In a lamp, the combination of a body, a reflector therein, means to pivotally connect said reflector at one side of its focal axis to said body, means to swing the reflector in said body, a connector slidably in an opening in the rear end of the reflector, a bulb in the front end of said connector, and means attached to the rear end of the connector to move the connector forward relative to the reflector and toward said pivoting means when the reflector is swung back in said body.

CHARLES E. GODLEY.
